VICTOR FÜRTH, OF COLOGNE-MULHEIM, GERMANY, ASSIGNOR TO FELTEN & GUILLE-AUME CARLSWERK ACTIEN-GESELLSCHAFT, OF COLOGNE-MULHEIM, GERMANY.

STRANDING MACHINE FOR THE MANUFACTURE OF WIRE ROPES FREE FROM TWIST

Application filed December 9, 1926, Serial No. 153,679, and in Germany May 31, 1926.

In braiding or laying the wires to form strands or ropes, the wires are bent into a helical shape. This laying is however not able to do away with the resilience in the wire to such an extent that the helically bent wire will no longer spring back. In order to prevent or counteract this springing back it has already been proposed to pass the wires, before they are braided or laid, through a former, which imparts to them the helical line or pitch they are to occupy in the finished strand or in the rope. In this former the wires are bent in such a manner that they no longer have a tendency to spring back. 10 It has been proposed, among other suggestions, to use a tapered drum as the former, consisting of independently movable tapered sections on which grooved discs or rollers are mounted, over and under which the wires are passed, so that, when the drums revolve, they are bent into a helical shape. This arrangement however, is complicated, inconvenient and costly and no means are provided for preventing the helically bent wires from 20 twisting about their own axes, when the drums revolve and of thereby preventing the occurrence of internal strains in the wires. The invention is clearly illustrated in the accompanying drawing, in which:—

30 Fig. 1 is enlarged side elevational detail of the improved roller forming device, and Fig. 2 is a diagrammatic view of the device with prebending means in connection therewith.

35 Referring now, more particularly to the drawings, supporting arms *b* are provided on the laying frame *a*, through the hollow shanks of which wires *d* are introduced in the suitable direction and position. These 40 supporting arms are provided on the stranding head, being secured to the front disc *x* of the head by nuts *y* which are directly engaged on the threaded portions of said arms *b*. These arms are preferably inclined to 45 wards the stranding point according to the direction of the wires *d* coming from the reels *v* so that the feeding of the wires can take place through the hollow shaft towards the preshaping point without any deflecting 50 of the wire. On the supporting arms *b* grooved discs or rollers *c* are mounted in such a manner that the wires passing through between them are bent into a helical shape during the operation of the stranding machine. In order to be able to adjust the rollers according to the thickness of the wires used or the desired helical form or pitch, the rollers *c* may be so arranged on the supporting arms that they can be adjusted in their longitudinal direction or at right angles thereto. 55 Preferably the two outer rollers of each supporting arm are made adjustable in the longitudinal direction as shown in dotted lines of Fig. 1 and only the middle roller is made adjustable at right angles to the said longitudinal direction. Owing to the required pulling forces being small, the wires which are prebent by means of this device are not damaged or subjected to any preliminary 60 stresses and they retain the helical form imparted to them corresponding to the pitch of the finished rope also on the portion from the prebending point up to the stranding point. As soon as the wires leave the rollers *c* they immediately drop, owing to their helical form, into the shape of the rope *k* around the rope core *g* of hemp or wire. For effecting the laying of the wires the laying frame *a* and with it the bobbins containing the wires 65 are revolved about the axis of the rope or the core *g*. In braiding and laying machines in order to prevent a twisting of the preliminarily bent wires about their own axes, the bobbins in the laying frame are given the usual reverse rotary motion, so that they 70 always retain their initial position in space and the wires will not be twisted. Wire ropes made in this manner from wires which have been preliminarily bent so as to be free 75 from strain are completely free from the tendency to untwist, in other words, the laid wires have no tendency to turn in the reverse direction, do not spring out, and the finished rope will not warp and will not form kinks. 80 Fig. 2 shows the arrangement of the roller prebending device *u* in the stranding machine, the wire reels *v* of which through the intermediary of a transmission gear *w* during 85 the operation of the stranding machine receive a twist such that the reels always retain 90 95 100

the vertical position shown, so that by this reverse rotary motion an axial twisting of the prebent wires is avoided during stranding.

5 What I claim is:

1. A device for the manufacture of wire ropes free from twisting in which the pre-bending of the wires is effected between rollers, comprising in combination with the rollers and with a stranding head having discs, supporting arms for the said rollers and means for detachably and rigidly securing the said supporting arms onto the front disc of the stranding head, the said supporting arms having hollow shafts through which the wires can be fed to the rollers.
2. A device as claimed in claim 1 in which the supporting arms are so inclined towards the stranding point that the center lines of the supporting arms lie on the periphery of a cone, the axis of which coincides with the stranding axis.
3. A device as claimed in claim 1 having reels on the stranding head capable of reverse rotation for the purpose of preventing a twisting of the prebent wires.
4. A device for manufacturing wire ropes free from a tendency to untwist as claimed in claim 1, and in which the rollers are arranged so as to be capable of adjustment.
5. A device for the manufacture of wire ropes free from a tendency to untwist as claimed in claim 1, and in which the outer rollers are adjustable in the longitudinal direction of the supporting arms.
6. A device for manufacturing wire ropes free from a tendency to untwist as claimed in claim 1, and in which the central rollers are adjustable at right angles with respect to the longitudinal direction of the supporting arms.

In testimony whereof I have signed my name to this specification.

VICTOR FÜRTH.
